UNITED STATES PATENT OFFICE.

WILMER W. WESTRUP, OF CHIHUAHUA, MEXICO.

MASSAGING IMPLEMENT.

1,198,799.

Specification of Letters Patent. Patented Sept. 19, 1916.

Application filed November 15, 1915. Serial No. 61,616.

To all whom it may concern:

Be it known that I, WILMER W. WESTRUP, a citizen of the United States, residing at Chihuahua, in the State of Chihuahua, Mexico, have invented a new and useful Massaging Implement, of which the following is a specification.

This invention relates to a massaging implement and one of its objects is to provide a device of this character utilizing an applicator having flexible fingers through which extend openings in communication with a suction pump adapted to operate intermittently for creating a suction through the fingers whereby during the movement of the applicator over the surface being treated, this intermittent suction will operate to withdraw impurities from the pores as they are opened by the movement of the fingers.

20 A further object is to provide simple means whereby the applicator is given a circular motion thus to produce a kneading action, the motion being produced by simple and compact mechanism which will not readily get out of order and which requires but little power to operate it.

25 A further object is to provide suction means carried by the mechanism employed for operating the applicator.

30 Another object is to provide an implement of this character which is cheap to manufacture and can be conveniently manipulated.

35 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

40 In the accompanying drawings the preferred form of the invention has been shown.

In said drawings:—Figure 1 is a section through the massaging implement. Fig. 2 is an elevation thereof. Fig. 3 is a view similar to Fig. 2 but showing all but the top portion of the cover plate removed, said top portion being shown in section. Fig. 4 is a section on line A—B Fig. 3.

45 Referring to the figures by characters of reference 1 designates a casing section which can be of any desired contour and proportions and which is provided, adjacent one

end, with an outstanding boss 2 exteriorly screw threaded. This section 1 has an end wall 3 in which is formed a substantially semi-cylindrical recess 4 and an angular recess 5. The angular recess is adapted to receive a bearing block 6 having a recess 7 therein which is substantially semi-spherical. A cover section 8 is arranged upon the section 1 and has an end wall 9 provided with recesses 10 and 11 corresponding with and directly opposite the recesses 4 and 7 respectively. A bearing block 12 similar to the block 6 is seated in the recess 11. The two sections 1 and 8 may be detachably connected in any manner desired, as by means of screws 13. An end wall 14 extends from the section 8 and laps the section 1 so that when the two sections are assembled, they will form a housing in one end of which is provided a circular opening formed by the opposed recesses 4 and 10.

Engaging the boss 2 is a hollow handle 15. This handle may be secured in place by screwing it onto the boss, or by fastening it in any other manner desired. Extending longitudinally through the handle and journaled within the boss 2 is a drive shaft 16 at one end of which is provided a disk-like head 17 seated within a recess 18 in the inner face of the section 1. A collar 19 is secured to the shaft at a point within the handle 15 and bears against the boss 2 to hold shaft 16 against longitudinal displacement. The shaft 16 may be suitably connected to a flexible driving shaft 20 or to any other suitable means for actuating it.

Extending from the head 17 is a wrist pin 21 projecting through a slot 22 formed longitudinally within a lever 23. This lever has a ball 24 formed integral therewith and bearing within the recesses in the blocks 6 and 12, and projecting from the lever and through the recesses 4 and 10 is a stem 25 adapted to be detachably engaged by an applicator 26.

Formed on or secured to the lever 23 is a pump casing 27 which can be produced by enlarging the lever and forming a bore in the enlarged portion. A passage 28 extends from one end of this pump casing and through the ball 24 and the stem 25 so as to communicate with a chamber 29 formed within the applicator. Said applicator is preferably provided with flexible fingers 30 of rubber such as commonly employed in connection with massage implements, but these fingers differ from the usual ones in

that they have openings 31 extending through them from the extremities thereof, these openings communicating with the chamber 29.

- 5 Fixedly connected to the wrist pin 21 so as to rotate therewith, is a crank arm 32 which is in turn pivotally connected to a pitman 33 attached to a piston 34 mounted for reciprocation in the pump casing 27.
- 10 The piston may be formed with one or more openings 35 therethrough adapted to be closed by a valve 36 so that during the movement of the piston toward the passage 28, air will escape through the openings 35, whereas during the movement of the piston in the opposite direction, valve 36 will close the openings 35 and a suction will be set up through the openings 31 and chamber 29 into passage 28 and casing 27.
- 15 20 The slotted portion of the lever 23 is offset or obliquely disposed as shown particularly in Fig. 1 and formed on or secured to the wrist pin 21 at the sides of the lever 23 are deflecting ribs 37 constituting cams.
- 25 These ribs or cams are so shaped as to cooperate with the obliquely disposed faces of lever 23 to impart a lateral swinging movement to the lever during the rotation of the shaft 16.
- 30 It will be obvious that during the rapid rotation of the shaft 16, the wrist pin 21, by traveling in a circular path, will work successively against the side walls of the slot 22, thus to swing the lever 23 in one 35 plane while at the same time the cams or ribs 37 will work successively against the respective sides of the inclined or diagonally disposed portions of the lever 23 so as to oscillate said lever in a plane extending at 40 right angles to the first plane of movement. The compound movement thus set up as a result of the two actions mentioned will cause the applicator 26 to set up a kneading action upon the surface being treated, thus 45 to spread open the pores and loosen any impurities contained therein. At the same time the piston 34 will be rapidly reciprocated, setting up a rapid intermittent suction through the openings 31 so that the 50 loosened impurities within the pores will thus be removed.

Importance is attached to the fact that the suction means is carried by the lever 23 to which the applicator is connected, thus 55 greatly simplifying the mechanism and enabling the apparatus to be cheaply and compactly constructed without danger of getting out of order.

By removing the section 8 all of the mechanism in the implement is exposed and can be readily inspected, oiled and repaired.

What is claimed is:—

- 60 65 1. A massaging implement including a casing, a lever mounted for universal swinging movement, an applicator connected to

the lever, revoluble operating means within the casing and engaging the lever for oscillating said lever in one plane of movement, means coöperating with the lever and carried by said revoluble means for oscillating the lever transversely of said plane of movement, and means carried by the lever and driven by said revoluble element, for setting up an intermittent suction through the applicator.

70 75 80 85 90 95 100 105 110 115 120 125 130 2. A massaging implement including a casing, a lever mounted for universal movement within and extending beyond the casing, an applicator connected to the lever and having projecting fingers formed with apertures extending from the extremities thereof, revoluble means within the casing for simultaneously oscillating the lever in two directions thereby to impart a kneading action to the applicator, and means movable with the lever and driven by said revoluble means, for setting up an intermittent suction through the applicator.

3. A massaging implement including a casing, a lever mounted for universal movement therein and projecting beyond one end of the casing, a hollow applicator connected to the lever and having flexible fingers formed with openings extending therethrough from the extremities thereof, revoluble means within the casing for imparting universal movement to the lever and applicator, a pump carried by the lever and in communication with the applicator, and means operated by said revoluble means for operating the pump to set up an intermittent suction through the applicator.

4. A massaging implement including a casing, made up of detachably connected sections, a lever mounted for universal movement within the casing and having one end projecting therebeyond, a hollow applicator connected to the lever and having openings therein, a revoluble drive element, means operated thereby for imparting universal movement to the lever, a pump carried by the lever, means for actuating the pump during the movement of the lever, for setting up an intermittent suction through the applicator.

5. A massaging implement including a casing, a handle extending therefrom, a shaft journaled within the casing and extending through the handle, a lever mounted for universal movement within the casing and having one end projecting from the casing, a hollow applicator connected to the lever and having inlet openings, means operated by the shaft and coöperating with the lever for imparting universal movement to the lever, a pump carried by the lever, and means operated by the shaft for actuating the pump to set up an intermittent suction through the applicator during the movement of the lever and applicator.

6. A massaging implement including a casing, opposed bearing members therein, a lever having a ball engaging the bearing members; there being an integral pump casing upon the lever and having an air inlet extending from one end of the lever, an applicator carried by the lever and having air inlets in communication with the inlet of the pump casing, a wrist pin mounted 5 for rotation within the casing and coöperating with the lever for operating the lever, means on the wrist pin and coöperating with the sides of the lever during the ro-

tation of the wrist pin for oscillating the lever in another direction, a piston within 15 the pump casing, and means operated by the wrist pin for reciprocating the piston to set up an intermittent suction through the applicator.

In testimony that I claim the foregoing 20 as my own, I have hereto affixed my signature in the presence of two witnesses.

WILMER W. WESTRUP.
